UNITED STATES PATENT OFFICE

2,485,498

MUSICAL INSTRUMENT

Harry Lewis, Gainesville, Tex.

Application May 14, 1947, Serial No. 747,973

5 Claims. (Cl. 84—296)

1

This invention relates to musical instruments. It is an object of the present invention to provide a combined string instrument and a needle sound reproducer to which the vibrations of the string are transmitted for the purpose of being reproduced through a horn fixed to the instrument.

Other objects of the present invention are to provide a musical instrument employing a string and a reproducer which is of simple construction, inexpensive to manufacture and efficient in operation.

For other objects and for a better understanding of the invention, reference may be had to the following detailed description taken in connection with the accompanying drawing, in which

Fig. 1 is a side elevational view of the combined string device and horn.

Fig. 2 is a top plan view of the instrument.

Fig. 3 is an enlarged cross-sectional view of the instrument taken on line 3—3 of Fig. 1.

Fig. 4 is a cross-sectional view, in elevation, taken on line 4—4 of Fig. 3.

Fig. 5 is a cross-sectional view taken on line 5—5 of Fig. 4.

Fig. 6 is a perspective view of a wood or leather piece disposed between the needle arm and the diaphragm.

Fig. 7 is a perspective view of leather faced piece of wood on which rests a device for connecting the needle arm to the string.

Figs. 8 and 9 are fragmentary top and side elevational views showing a modified form of attachment of the needle to the string.

Fig. 10 is a fragmentary top plan view of a modified form of arrangement where the reproducer is set in the long neck.

Fig. 11 is a transverse cross-sectional view taken on line 11—11 of Fig. 10.

Referring now to the figures, 15 represents a long wood piece on the rear end of which is disposed a chin rest 16 and in the forward end of which is a slot 17 into which a string 18 is extended to be tightened by a tightening key 19. The string 18 is connected at the rear of the wood piece to a post 21 and is extended forwardly and over a bridge 22. The string 18 is a banjo E string and is made out of wire.

On the bottom of the piece 15 there is connected a reproducer 24 which is of hollow construction and serves as a support for a diaphragm 25. The support 24 has a flange 26 and the diaphragm 25 is connected to the flange by a ring 27 and screws 28. A gasket 29 may be disposed between the diaphragm 25 and the flange 26, Fig. 5. The

2

reproducer 24 has a sleeve projection 31 into which is extended the small end of a horn 32. The horn is secured to the sleeve projection 31 by a set screw 33. The diaphragm is made of aluminum, mica or brass and to its center there is secured a needle arm 35. Between the arm 35 and the diaphragm above its point of connection, there is disposed a leather block 36 having a groove 37 for receiving the needle arm 35. The needle arm 35 has an inturned end 38 which is connected to the center of the diaphragm. Attaching plates 39 on opposite sides of the diaphragm and threadingly locked with the inbent end 38 of the needle fixes the needle to the diaphragm so that vibrations transmitted through the needle will be transmitted to the diaphragm.

The ring 27 has a lug projection 41 to which the needle arm 35 is pivotally connected by a pin 42 extending through the projection. The upper end of the needle arm has an inwardly bent portion 43 which rests upon a block 44 having a top leather facing 45 with a groove 46 therein for receiving the inbent portion 43. Connected to the string 18 is a peg 48. The peg 25 extends upwardly to receive the string 18. The inbent end of the needle arm has a sleeve formation 49 for receiving the peg 48 and the peg is made secure therein by a set screw 50. The instrument is played with a bow while it is held under the chin in the same manner as a violin. The instrument can also be played while holding the same between the legs. The vibrations from the string are transmitted to the needle by the peg 48. The inbent end 43 of the needle arm 35 is slidable in the groove 46 of the block piece. These vibrations are extended through the needle and to the diaphragm 25 whereby they will be imparted to the horn 32.

Referring now particularly to Figs. 8 and 9, the peg 48 extends through the inbent end of the needle arm as indicated at 52 but the arm has wing extensions 53 with openings therein for receiving screws 54 which attach the same to leather formations 55 mounted on the reproducer 24. The leather has sufficient resiliency to permit the vibration of the needle arm.

In Figs. 10 and 11, there is shown a modified form of the invention wherein the reproducer 24 is inserted in a recess 56 in the bottom of the long neck so that the main portion of the reproducer extends wholly directly beneath the long neck. The needle arm, as indicated at 57, is pivoted on a bracket 58 and has a sleeve portion 59 on its upper end to which peg 48 is attached and secured by a set screw 61. In this construc-

tion, the block 44 is dispensed with. The end of the arm 57 is free and the peg 48 is rested upon a block 62 which is of different shape than the block 44 and rests wholly on the top of the neck.

While various changes may be made in the detail construction, it shall be understood that such changes shall be within the spirit and scope of the present invention as defined by the appended claims.

I claim:

1. In a musical instrument having an elongated wood piece, a string extending longitudinally along the top of the wood piece and connected therewith by a projection and by a bridge over which the string can be stretched to be tightened, a tightening piece for the string adjustable in one end of the piece, a reproducer connected to the wood piece including a support and diaphragm, and a horn extending from the reproducer support; a needle arm pivoted upon the reproducer support and connected to the center of the diaphragm, the upper end of the needle arm being inwardly bent, a peg element connected to the wire string and to the inbent portion of the needle arm, and a sound deadening member mounted on the support and positioned to engage the said inbent portion of the needle arm.

2. A musical instrument as defined in claim 1 in which the sound deadening block includes a leather facing with a groove therein disposed beneath the inbent end of the needle arm and over which the needle arm inbent end can slide.

3. A reproducer for a string instrument having a sound reproducing element including a diaphragm stretched over a cup-shaped support, an arm pivotally mounted on said support and positioned with one end in engagement with the diaphragm and the other extended over one side of the support, a wood block mounted on the support and positioned under the extended end of the arm, a fibrous vibration absorptive facing between the extended end of the arm and block, and a peg carried by the extended end of the arm and adapted to be influenced by a string of the instrument.

4. A reproducer for a string instrument having a sound reproducing element including a diaphragm stretched over a cup-shaped support, an arm pivotally mounted on said support and positioned with one end in engagement with the diaphragm and the other extended over one side of the support, a wood block mounted on the support and positioned under the extended end of the arm, a fibrous vibration absorptive facing between the extended end of the arm and block, a peg carried by the extended end of the arm and adapted to be influenced by a string of the instrument, and a fibrous sound deadening block positioned between the arm and diaphragm.
5. A reproducer for a string instrument having a sound reproducing element including a diaphragm stretched over a cup-shaped support, an arm pivotally mounted on said support and positioned with one end in engagement with the diaphragm and the other extended over one side of the support, a wood block mounted on the support and positioned under the extended end of the arm, a fibrous vibration absorptive facing between the extended end of the arm and block, and a peg adjustably mounted on the extended end of the arm and adapted to be influenced by a string of the instrument.

HARRY LEWIS.
